(57) **CLAIM**

I claim the ornamental design for automatic pour over coffee maker, as shown and described.

DESCRIPTION

FIG. 1 is a front view of an automatic pour over coffee maker showing the new design;

FIG. 2 is a rear view thereof;

FIG. 3 is a bottom plan view thereof;

FIG. 4 is a top plan view thereof;

FIG. 5 is a right-side perspective view thereof;

FIG. 6 is a left-side perspective view thereof;

FIG. 7 is a bottom perspective view thereof; and,

FIG. 8 is a top perspective view thereof.
